FIG. 3

On the left side, there is a vertical navigation menu with the following items:

- WELCOME
- ABOUT YOU
- MEET THE TEAM
- PAPERWORK (highlighted)
- BENEFITS
- WHAT WE DO
- NEXT STEPS

The 'PAPERWORK' section contains several sub-sections, each with a small icon and a title:

- Form 1-9 (Icon: Document): This form verifies your identity and your eligibility to work in the United States. See Env 1 (5/4/2015) (FILE OUT)
- Form 1-9 (Icon: Document): Tax Withholdings. These forms will set up tax withholdings for the year.
- Company Policies (Icon: Book): The list of policies that you need to read and acknowledge. See Env 3 (5/4/2015) (FILE OUT)
- Emergency Contact (Icon: Phone): Tell us who to call in case of an emergency. (FILE OUT)
- Direct Deposit (Icon: Bank): Get fast deposits by an account of your choice instead of your paper check.
- Get Paid Faster (Icon: Clock): (FILE OUT)

At the bottom of the screen, there is a large, bold, blue button labeled 'GET STARTED'.
